UNITED STATES PATENT OFFICE

NICOLA G. DE MARCO, OF CHICAGO, ILLINOIS, ASSIGNOR TO ALFRED DECKER & COHN, INC., OF CHICAGO, ILLINOIS, A CORPORATION OF ILLINOIS

COAT BELT

Application filed March 21, 1932. Serial No. 600,210.

This invention relates to coats, and more particularly to coats, such as overcoats, having belts of one form or another.

Generally stated, the object of the invention is to provide a novel and improved construction and arrangement whereby the coats, such as overcoats for men, may be provided with belts which are adjustable, or which are detachable in part, whereby the coat may be worn with either a full belt, or with only a partial belt effect at the back, if so desired.

It is also an object to provide certain details and features of construction and combinations tending to increase the general efficiency and the desirability of a coat-belt arrangement of this particular character.

To the foregoing and other useful ends, the invention consists in matters hereinafter set forth and claimed and shown in the accompanying drawing, in which—

Fig. 1 is a rear elevation of an overcoat having a belt embodying the principles of the invention;

Fig. 2 is a similar view, with the upper portion of the coat shown broken away for convenience of illustration, and with the two end portions of the belt unbuckled and detached, thereby leaving only a belted effect at the back of the coat;

Fig. 3 is an enlarged rear elevation of a portion of the belt construction, showing the connections for detaching the end portions of the belt;

Fig. 4 is an inside view of the attachable end portion of one of the detachable sections of the belt, showing the hooks thereof;

Fig. 5 is an enlarged horizontal detail section on line 5—5 in Fig. 1 of the drawing.

As thus illustrated, the overcoat 1 may be of any suitable, known or approved style or design. Preferably, in style, it is a coat of that type which is most suitable or appropriate for a belted effect around the waist thereof.

As shown in the drawing, which is illustrative of one form of the invention, the belted effect is produced by a rear back section 2, of preferably the same kind of cloth from which the coat is made, the ends of this back section being secured to the body of the coat,

preferably at the side seams 3 thereof, by the stitching 4. Preferably, as shown, the seams 3 are in the form of so-called lap seams of suitable width. The belt straps or loops 5 are preferably of substantially the same width and are sewed to the lap seams by stitching 6, at the ends of each belt strap or loop, as shown in the drawing. In this way, the cloth loops 5, preferably made of the same cloth from which the coat is made, 66 cover the ends of the back section 2 of the belt, and in sewing the parts together, the wire loops 7 are sewed in place between the coat and the under side of the section 2, by stitching 8 through the eyes of said wire 65 loops, in the manner shown, whereby the straight outer ends of these wire loops are just a little beyond the ends of the section 2, as shown more clearly in Fig. 2 and Fig. 3 of the drawing.

The end portions of the belt are composed of detachable sections 9, one of which has the buckle 10 at the end thereof, adapted to engage the free end portion of the other detachable section. These detachable sections 75 are provided, at their detachable ends, with wire hooks 11, of a shape to engage the loops 7, attached in place by stitching 12 through the eyes of these hooks. As shown more clearly in Fig. 5, the hooks 11, and also the 80 loops 7, may be inserted between the outer cloth and the lining of the sections 2 and 9, and sewed in place therein, whereby only the outer ends of the said wire loops and hooks will be exposed when the detachable sections 85 9 are disconnected from the fixed belt section 2 of the belt, as it will be understood that the three sections of the belt are preferably lined, similar to the coat, and perhaps interlined as well, depending upon the character of the materials.

Thus, when the sections 9 of the belt are hooked in place, by engaging the wire hooks 11 in the wire loops 7, the joint thus formed between the fixed section 2 and the detachable sections 9 is concealed by the belt straps or loops 5, previously described. Under such conditions, with the three sections of the belt detachably connected together, the front end portions of the belt can be coupled to 100

gether by the buckle, in the ordinary manner. However, if it be desired to wear the coat with a different belt effect, as with only a partial belt across the back of the coat, the sections 9 can be detached, and only the fixed section 2 of the belt will then remain at the back of the coat. In this way, the two styles of belted coat are combined in one, either the full-belted or partial-belted coat, and the belt may be changed from one to the other at the will of the wearer.

Thus it will be seen that the back section 2 of the belt serves as an element of both effects, for it not only serves to produce the partially belted effect, but it also serves to contribute to the full belted effect.

What I claim as my invention is:

1. In an overcoat, a three-section belt therefore made of the same goods to match the coat, having a fixed or permanent back section secured at its ends across the back of the garment, and having detachable end sections which are separably connected to the garment at points where the back section is connected to the coat, whereby the garment may be worn with either a full-belted or a partially-belted effect, with said back section serving for both effects.

2. A coat as specified in claim 1, the fixed back section having its ends sewed to the side seams of the coat, so that the joints between the sections of the belt coincide with these seams, and belt loops extending over and covering said joints, the ends of the loops being sewed to the side seams.

3. A coat as specified in claim 1, said fixed and detachable belt sections having their engaging ends provided in effect with concealed hook and eye devices, whereby the detachable sections can be readily hooked to or unhooked from the fixed section.

4. A coat as specified in claim 1, said fixed and detachable belt sections having engaging ends provided in effect with hook and eye devices, whereby the detachable sections can be readily hooked to or unhooked from the fixed section, together with belt loops extend-

ing over and covering the hook and eye joints between the belt sections.

5. A coat as specified in claim 1, comprising means to cover the joints between the fixed section and the detachable sections of the belt.

6. In an overcoat, a belt therefor having fixed or permanent back section secured to the back of the garment, and having detachable end sections which are separable from said back section, whereby the coat may be worn with either a full-belted or a partially-belted effect, with said back section serving for both effects, the fixed back section having its ends sewed to the side seams of the coat, so that the joints between the sections of the belt coincide with these seams, and belt loops extending over and covering said joints, the ends of the loops being sewed to the side seams.

7. In an overcoat, a belt therefor having a fixed or permanent back section secured to the back of the garment, and having detachable end sections which are separable from said back section, whereby the coat may be worn with either a full-belted or a partially-belted effect, with said back section serving for both effects, said fixed and detachable belt sections having engaging ends provided in effect with hook and eye devices, whereby the detachable sections can be readily hooked to or unhooked from the fixed section, together with belt loops extending over and covering the hook and eye joints between the belt sections.

8. In an overcoat, a belt therefor having a fixed or permanent back section secured to the back of the garment, and having detachable end sections which are separable from said back section, whereby the coat may be worn with either a full-belted or a partially-belted effect, with said back section serving for both effects, comprising means to cover the joints between the fixed section and the detachable sections of the belt.
